UNITED STATES PATENT OFFICE

2,602,453

FILTER TIP FEED MECHANISM FOR FILTER
TIP CIGARETTE-MAKING MACHINES

Frederick Richard Treble, Luton, England, assignor to Amalgamated Tobacco Corporation, Limited, Luton, England, a company of Great Britain and Northern Ireland

Application June 28, 1949, Serial No. 101,717
In Great Britain July 2, 1948

1 Claim. (Cl. 131—94)

1

This invention relates to feed mechanism especially to mechanism for feeding filter tips to machines for manufacturing filter tip cigarettes. This invention is particularly concerned with apparatus for manufacturing filter tip cigarettes as described in the specification of my copending application Serial No. 43,357 filed August 10, 1948, now abandoned.

The aforesaid specification describes a machine for assembling filter tip cigarettes comprising inter alia a carrier member of cylindrical form grooved longitudinally to receive pre-formed double-length cigarettes and double-length filter plugs from related hoppers for conveyance to a travelling paper web for wrapping in the known manner and subsequent severing for the production of filter tip cigarettes.

It has been discovered that in the charging of the hopper for the filter plugs there is a tendency for the filter plugs, due to their short length, although double the normal filter plug length, to become out of alignment and awkwardly placed so that a continuous feed from the hopper to the carrier member is not conducted smoothly without a break in the supply causing difficulties. Furthermore it is a slow and tedious process to fill a hopper with short lengths of filter plugs.

The object of the present invention is to obviate the aforesaid disadvantages and to this end filter plugs are used of at least four times the standard length filter plug, a grooved carrier member being provided to transfer the plugs from a hopper to the assembly mechanism, said carrier member being grooved circumferentially to permit the passage of a rotary knife whereby the lengths of filter material are sub-divided during this passage from the hopper to the assembly mechanism and whilst held by the carrier member.

Preferably the plug carrier is rotated at the same speed as a rotary cigarette carrier but has half the number of grooves as that in the cigarette carrier, one half of the divided filter plug dropping during the passage of the plug carrier member into a magazine of an assembly mechanism and the other half of the plug drops on to a fixed platform so that on the next movement of the carriers the remaining half filter on the fixed platform is displaced by plunger mechanism to enter the said magazine; as there are only half the number of grooves in the plug carrier relative to the cigarette carrier, a filter plug is not dropped from the plug carrier during this movement as a blank position on the plug carrier will register with the magazine. The angular

displacement of the two carriers is the same for each movement.

One form of apparatus according to this invention is illustrated diagrammatically in the accompanying drawings, wherein:

Fig. 1 is a side elevation, partly in section.

Figs. 2 and 3 are transverse sectional elevations taken on lines II—II and III—III, respectively, of Fig. 1, and

Fig. 4 is a fragmentary side elevation, similar to Fig. 1 but showing parts in another position.

The filter tip cigarette assembling machine is provided with a double hopper 11, wherein one side 12 receives double length cigarettes, and the other side 13 receives filter tip plugs which each are four times the length of the finished filter tip plug. The long cigarettes and the long plugs are separated in the hopper by a thin partition 14.

20 A rotatable drum assembly is provided comprising a cigarette drum 15 and a filter-tip plug drum 16, both of said drums being axially aligned on and keyed to a driving spindle 17 so that both drums rotate simultaneously with the spindle. Preferably the drive to the spindle 17 is continuous, but may be intermittent, and is effected in any suitable manner. Both drums are of equal diameters. The cigarette drum 15 is provided with a number, for example, twenty, of longitudinal grooves 18 in its periphery, circumferentially spaced apart, whilst the filter-tip plug drum 16 is provided with similar grooves 19 but only half the number of those in the drum 15, that is, in the example, ten grooves 19 in the drum 16.

25 Cigarettes 20 drop out of the hopper 12 into the grooves 18 in the drum 15, whilst filter-tip plugs 21 drop out of the hopper 13 into the grooves 19 in the drum 16. The drums rotate clockwise, Figs. 2 and 3, and the cigarettes and plugs are retained in the grooves by retaining strips 22, 23, respectively which conform generally to the peripheries of the drums.

30 Refusal rollers 24, 25 are associated with the hoppers 12 and 13, and the drums 15 and 16 respectively, in the known manner.

35 Whilst the plugs 21 are held in the grooves 19 of the drum 16 they are cut into halves by a circular knife 26 which is driven at high speed and of which the cutting edge projects into an annular groove 27 in the drum 16.

40 Cigarettes drop out of the grooves 18 in the drum 15, when the respective grooves are at the bottom of the drum, into a magazine 28. Similarly, the half of each filter-tip plug nearer the cigarette, the left-hand half in Fig. 1, drops out

of the groove 19 in the drum 16 into the magazine 28, the other half of each plug remote from the cigarette, the right-hand half in Fig. 1, falls on to a fixed platform 29 which is elevated above the bottom of the magazine 28. The magazine 28 may be adapted to hold two or more cigarettes, one above another, and a similar number of plugs.

As the number of spaced grooves in the drum 16 is only half the number of grooves in the drum 15, cigarettes will drop out of two successive grooves 18 whilst half plugs are dropping out of only one groove 19. At one position in the simultaneous rotation of the drums 15 and 16, a cigarette will drop out of a groove 18 into the magazine 28, a half-plug will drop out of a groove 19 into the magazine 28, and the other half plug will drop out of the same groove 19 onto the platform 29. At the next position in the rotation of the drums, a cigarette will drop out of the next groove 18, but there will be no groove 19 registering with the magazine and consequently no plug or half-plugs will drop into the magazine or on to the platform from the drum 16, but the half-plug now resting on the platform 29 will be pushed, by means hereinafter described, into the magazine 28.

The bottom double-length cigarette and double-length filter in the magazine 28 lying on the platform 30 which constitutes the floor of said magazine, and which are now substantially in axial alignment, are transferred to the cigarette garniture or paper folder 31 in the manner described in my aforementioned application Serial No. 43,357, that is, by a lug 32 on an endless chain 33 which abuts the end of the filter plug and pushes the two components along the platform 30 into the garniture, the lug 32 projecting into the magazine 28 through a slot 34 in the platform 30. As one complete cigarette and filter plug is pushed out of the magazine 28 by the lug 32 the next higher cigarette and plug in the magazine descends onto the platform 30.

The half plug disposed on the platform 29 is pushed towards the drum 15 and into the magazine 28 by a ram 35 adapted to be projected through a guide sleeve 36 on the wall 37 by suitable operating means (not shown) timed so as to project the ram through the wall 37 approximately at the moment when a cigarette is falling out of the drum 15 but no plug is falling out of the drum 16; consequently two half-plugs which were aligned in one groove 18 of the drum 16 now become disposed one above the other in the magazine 28, thereby ensuring that each cigarette descending from the drum 15 is provided with a filter plug when it reaches the platform 30.

The double-length cigarettes and filter plugs are wrapped in the garniture 31 in paper 38 passing around rollers 39, and thereafter they are severed in the known manner to form normal length filter tipped cigarettes.

It will be appreciated that the gearing employed

for effecting the timed operational relationship of the various parts follow accepted practice. A cigarette 20 will drop from the drum 15 into the magazine 28 at intervals at the end of each movement of the drum equal to the angular spacing between grooves 18, whilst the front half of a plug 21 will drop from the drum 16 into the said magazine and the rear half of the same plug will drop onto the platform 29 at twice the said intervals, that is, at intervals equal to the angular spacing between the grooves 19.

The invention has been described more particularly for use with the filter tip cigarette machine disclosed in the specification of my application Serial No. 43,357, but it is to be understood that the apparatus for delivering filter plugs and their severance to useful lengths may be applied to other types of filter tip cigarette forming machines.

What I claim and desire to secure by Letters Patent is:

A machine for making filter-tip cigarettes, comprising a longitudinally grooved rotary filter-tip plug carrier, a longitudinally grooved rotary cigarette carrier, both carriers being disposed in axial alignment and being adapted for synchronous rotation, the plug carrier having half the number of grooves of the cigarette carrier, separate charging hoppers associated with each said carrier, means for retaining cigarettes and plugs in the grooves of said carriers during approximately one half revolution of said carriers, said plug carrier having an annular groove located medially of the ends of said carrier, a rotary knife engaging in said annular groove whereby to cut in half plugs disposed in the longitudinal grooves in said plug carrier, a magazine disposed below said cigarette carrier and the adjacent half of said plug carrier, a fixed platform disposed below the other half of said plug carrier, the said platform being elevated above the floor of said magazine, a plunger device adapted to push plugs off said platform into said magazine, a second platform below said magazine onto which a cigarette and a half plug are received in adjacent end-to-end relation, an assembly mechanism for wrapping the cigarette and plugs and a mechanism for transferring the cigarette and the plug from the magazine to the assembly mechanism.

FREDERICK RICHARD TREBLE.
